F. K. HOTCHKISS
AUTOMATIC HOSE RETRIEVER

1,445,616

Filed Sept. 3, 1920

UNITED STATES PATENT OFFICE.

FRED K. HOTCHKISS, OF SAWTELLE, CALIFORNIA.

AUTOMATIC HOSE RETRIEVER.

Application filed September 3, 1920. Serial No. 407,976.

To all whom it may concern:

Be it known that I, FRED K. HOTCHKISS, a citizen of the United States, residing at Sawtelle, in the county of Los Angeles and 5 State of California, have invented new and useful Improvements in Automatic Hose Retrievers, of which the following is a specification.

It is the object of this invention to provide 10 a holder for hose and the like which is arranged to permit the hose to be drawn from the holder and which will automatically return the hose to the holder when it is released.

15 The invention is particularly applicable for use in connection with an automobile service station where it is desired to provide a plurality of hose lines leading from a water supply and an air supply. By means 20 of the present invention a plurality of hose lines are arranged within a single container and are each provided with means for returning the lines to the holder after using the same.

25 The invention will be readily understood from the following description of the accompanying drawings in which—

Figure 1 is a plan view with the top broken away of a device constructed in accordance with the invention.

30 Figure 2 is a vertical section on the line 2—2 of Figure 1.

Figure 3 is a detail section on the line 3—3 of Figure 1.

35 Figure 4 is an enlarged plan view of one of the guide rollers and its yieldable tensioning means.

In the drawings a casing is shown at 1 having the hinged top 2. A shaft 3 extends 40 transversely of the casing and is journaled in bearings 4 carried by the casing. Line handling wheels 5 and 6 are positioned upon the shaft 3 in spaced relation; one of said wheels, say the wheel 5, is fixed for rotation 45 with shaft 3, while the wheel 6 is journaled upon the shaft 3.

In the embodiment shown, conical containers 7 and 8 are positioned within the casing beneath the respective wheels, and said 50 containers are provided with openings 9 at their upper ends through which hose lines may pass into the containers. The containers are arranged within the casing so that the openings of the respective containers are 55 beneath diametrically opposite sides of the respective wheels. The front wall of casing

1 is provided with openings 10, and hose lines 11 and 12 extend through the respective openings. The hose line 11 is in alignment with wheel 6 and extends into the casing 1 over an idle pulley 13 and thence upwardly over wheel 6 and downwardly through the opening 9 of container 8 into said container. The hose is coiled within the conical container and its opposite end 65 extends outwardly through the container and through casing 1 and is connected to a suitable water supply.

The hose line 12 extends into casing 1 substantially in alignment with wheel 5 and 70 is guided by an idle pulley 14 to a point below wheel 5 and then extends upwardly around the back of wheel 5 and downwardly over the front of the wheel and into container 7 through the opening 9 of the same. 75 Within the containers the hose lines are coiled, as previously described, and the end of each extends through the container and the casing to a suitable air supply.

The hose lines are preferably held in position upon their respective wheels by means of rollers 15 received against the grooved peripheries of the wheels which receive the 80 hose lines. These rollers are preferably arranged at opposite sides of the wheels and are 85 journaled upon links 16 pivoted to the casing 1. The rollers at the opposite sides of a wheel may be yieldably held in position against the wheel by means of a bar 17 received at its opposite ends through lugs 18 90 upon the links supporting the respective rollers. The rod 17 is provided with heads 19 to prevent longitudinal displacement of the rod relative to lugs 18, and one end of the rod preferably extends beyond the lug 18, 95 with a spring 20 interposed between the head of the rod and the lug in order to yieldably swing the links 16 carrying the rollers toward one another and thereby form resilient 100 guide means for retaining the hose lines upon their wheels.

The wheel 6 which is journaled upon shaft 3, is provided with casing 22 extending axially from the wheel. A coil spring 23 is received within this casing with one end thereof fixed to shaft 3 and the other end of the same fixed to the casing. The spring is so arranged that when hose line 11 is drawn from casing 1, the other hose being held against inward movement—as by the contact of its nozzle with the outer casing 1 110 the rotation of wheel 6 and casing 22 will

cause the spring 23 to be tensioned. As a result, when the hose line 11 is released, casing 22 and wheel 6 will be reversely rotated for redrawing hose lines into casing 1. The 5 hose line will be drawn into its container and, due to the conical formation of said container, will be coiled within the same as clearly shown in Figure 2. When hose line 12 is withdrawn from casing 1, its wheel 5 will be rotated in the reverse direction to the direction in which wheel 6 is rotated when hose line 11 is withdrawn from the casing, hose 11 being in turn held against inward movement. This rotation of wheel 5 will 10 cause rotation of shaft 3 and a consequent tensioning of spring 23, so that when hose line 12 is released, it will be withdrawn into casing 1 and coiled in its container 7.

As will be obvious, withdrawal of both 20 hose at the same time will merely increase the tension on the spring 23, favorably to the return of both lines of hose.

It will be apparent that various changes 25 may be made in the construction, as thus set forth, without departing from the spirit of the invention.

What is claimed is:

1. The combination with a shaft, of a plurality of line-handling wheels mounted thereon, a spring having operating connection between said shaft and one of said wheels, and means connecting the other wheel to the shaft so that rotation of either of said wheels by the withdrawal of a line 35 thereover will tension said spring.

2. The combination with a shaft of a wheel fixed thereon, and a wheel journaled on said shaft, a coil spring secured to said shaft at one end and to said journaled wheel

at its opposite end, said wheels being arranged to be rotated in opposite directions for paying out flexible members from said wheels, the tension of said spring causing rotation of one of said wheels relative to the other wheel. 40

3. The combination with a container of a wheel, a flexible member normally coiled within said container and passing over and in frictional contact with said wheel, said wheel being adapted to be rotated in one direction by the withdrawal of said flexible member and a spring means tensioned by said rotation of the wheel and adapted to 45 reversely rotate the wheel and return the flexible member when said flexible member is released.

4. The combination with a container of a wheel and flexible member received within said container and passing over said wheel, guide rollers engaging said flexible member 50 and retaining the latter upon said wheel, said guide rollers being suitably supported and being connected by a tie rod with yieldable means engaging said rollers for drawing both rollers toward said wheel. 55

5. In a retriever for a plurality of lines, a wheel for handling each line, said wheels being adapted to be rotated in opposite directions by the withdrawal of a line thereover, a common shaft for said wheels, and 70 a spring connection between one of said wheels and said shaft, whereby the rotation of either wheel by the withdrawal of a line thereover will tension said spring. 65

In testimony whereof I have signed my 75 name to this specification.

FRED K. HOTCHKISS.
